UNITED STATES PATENT OFFICE.

JAMES A. O'NEIL, OF LYNN, MASSACHUSETTS, ASSIGNOR TO GENERAL ELECTRIC COMPANY, A CORPORATION OF NEW YORK.

ILLUMINATING DEVICE.

Application filed April 16, 1924. Serial No. 706,830.

My invention relates to illuminating devices. More particularly it relates to devices of this character in which reflectors are used.

5 It is often the case when a light unit is provided with a reflector that the region behind the reflector is deprived of so much light that the outline of the unit is lost and, therefore, the artistic effect of the 10 design is destroyed. Furthermore, the contrast presented between the light and dark regions is such that the unit becomes objectionable in that it produces a glare. It will be seen, therefore, that the ordinary street 15 lighting unit of artistic design may not be properly used, for example, as a flood lighting unit because of the shadow cast by the reflector which is ordinarily used.

It is an object of my invention to provide 20 a novel and improved type of reflector to avoid the objection above indicated. Therefore, artistic units may, as a result of my invention, be installed in front of buildings, a public building for instance, and 25 made to flood light the building by using a reflector of the type herein described without impairing the beauty of the unit as a whole.

The details of my invention are herein- 30 after more fully set forth and claimed, reference being had to the accompanying drawing. In the drawing, Fig. 1 shows a light unit with the novel reflector in elevation. Both the unit and reflector are shown in 35 section. Fig. 2 is a plan view of the reflector and its base support, and Fig. 3 is a view in sectional elevation of a light unit in which the perforated reflector is shown above the light source. Behind the 40 perforated reflector is shown a solid reflector for redirecting the rays that sift through the perforated reflector.

Referring more in detail to the drawing, the unit comprises a lamp 2 and a suitable 45 socket 3. The lamp projects through a central opening in the plate 4, which plate is secured to the collar 5, the latter resting on top of the frame 6. The globe 7 rests in turn upon the collar 5 enclosing the lamp 2 50 as well as the reflector 8, which latter is secured in any suitable manner about the lamp 2. As shown in the drawing, the reflector is provided with a flange 9 which is bolted or welded to the plate 4 as indicated. It 55 will be seen that if the reflector 8 were solid,

all of the light from the lamp 2 would be cut off from the major portion of the globe 7 which would give it an odd appearance. I have found that by perforating the reflector, as indicated in the drawing, a sufficient amount of light filters through the perforations to light up the globe all over and thereby preserving the pleasing effect of the design.

A reflector of this type may be made from 65 a silver plated copper or polished aluminum. The material from which the reflectors are to be made may be perforated beforehand and spun or formed into the desired shape. I have found that satisfactory results may 70 be obtained by using, for example, a mesh of 85 perforations to the square inch. In some instances the number may be increased to 120 or 210. The fineness or coarseness 75 of the mesh will be varied depending upon the results desired. It will be seen, therefore, that with my invention a small per cent of the light directed toward the reflector sifts through. I have found it satisfactory if in a unit area of the perforated 80 surface the light that goes through is 10% of the total light that would otherwise strike the area if it were not perforated. The size of the holes may also be varied to 85 let in more or less light. The amount of light that sifts through may be cut down by reducing the size of the openings or increased to 12%, for example, by increasing the size of the holes.

It will be understood that the principle 90 of my invention may be applied to reflectors of any shape or design. It is applicable as well to dome reflectors as to reflectors of other types. It will also be understood that the shape of the perforations may be varied. 95 They may be round, oblong, or square, for example. Toward the margin of the reflector the size of the perforations may be increased as indicated in Fig. 3, the object 100 being to avoid a sharp demarkation between the shadow cast by the edge of the reflector and the illuminated region unobstructed by any portion of the reflector. Instead of the larger size holes being provided along the 105 rim of the reflector serrated indentations may be substituted, the object being to allow the bright illuminated region to merge gradually into the shaded region without producing too sudden a contrast. The perforated reflector may be used in other relations than 110

within a globe. This is indicated, for example, in Fig. 3. In this figure the reflector is shown surrounding the source of light and presents the appearance of a dome, and above the perforated reflector there may be another reflector which serves to redirect the beams A and B which filter through the perforations.

The type of reflector shown in Fig. 3 will, of course, give symmetric distribution, but asymmetric distribution may be obtained by selecting a proper shape just as easily with the perforated reflector as with any other.

While I have shown and described a specific form of my invention, it will be understood that I do not so limit myself, inasmuch as variations will be readily sug-

gested as a result of the disclosure which will not depart from the spirit of my invention or from the scope of the claims herein. 20

What I claim as new and desire to secure by Letters Patent of the United States, is,—

A lighting unit comprising a globe, a source of light, a reticular trough reflector, said light source being located along the 25 axis of the globe, said reflector being located between the light source and the globe, the axis of the reflector extending transverse a plane at right angles to the axis of the globe and crossing the axis of the globe. 30

In witness whereof, I have hereunto set my hand this Twelfth day of April, 1924.

JAMES A. O'NEIL.
